CLAIM

The ornamental design for a bottle, as shown and described.

DESCRIPTION

FIG. 1 is a rear perspective view of the bottle;

FIG. 2 is a front perspective view of the bottle;

FIG. 3 is a top plan view of the bottle;

FIG. 4 is a rear elevational view of the bottle;

FIG. 5 is a left side elevational view of the bottle;

FIG. 6 is a front elevational view of the bottle; and,

FIG. 7 is a bottom plan view of the bottle.

The broken lines shown in the figures are for illustrative purposes only and form no part of the claimed design.
